UNITED STATES PATENT OFFICE.

SISSAK K. OUZOUN-BOGHOSSIAN, OF WASHINGTON, DISTRICT OF COLUMBIA.

DESIGN FOR A WATCH-MOVEMENT-CASE.

58,498.

Specification for Design.

Patented July 26, 1921.

Application filed August 16, 1920. Serial No. 403,945. Term of patent 3½ years.

To all whom it may concern:

Be it known that I, SISSAK K. OUZOUN-BOGHOSSIAN, a subject of the Sultan of Turkey, having declared my intention of becoming a citizen of the United States, residing at the city of Washington, District of Columbia, have invented a new, original, and ornamental Design for Watch-Movement-Cases, of which the following is a specification, reference being had to the accompanying drawing, forming part hereof.

The figure is a perspective view of a watch-movement-case, showing my new design.

I claim:

The ornamental design for a watch-movement-case, as shown.

In testimony whereof I affix my signature.

SISSAK K. OUZOUN-BOGHOSSIAN.
